UNITED STATES PATENT OFFICE.

EDWIN W. GOESER AND WILLIAM D. DAVIDSON, OF LOS ANGELES, CALIFORNIA, AS
SIGNORS TO UNION TOOL COMPANY, OF TORRANCE, CALIFORNIA, A CORPORATION
OF CALIFORNIA.

THREE-SPEED ROTARY DRAW WORKS.

Application filed June 25, 1923. Serial No. 647,549.

To all whom it may concern:

Be it known that we, EDWIN W. GOESER and WILLIAM D. DAVIDSON, citizens of the United States, residing at Los Angeles, in the county of Los Angeles and State of California, have invented a new and useful Three-Speed Rotary Draw Works, of which the following is a specification.

This invention relates to drum driving mechanism and particularly to this type of mechanism known popularly as "draw works" and which is used in the drilling operations for oil wells and other deep wells. The draw works includes a drum, and the mechanism for driving the same has heretofore included a low speed drive connection and a high speed drive connection, but in practical operation the high speed drive connection was not sufficiently high for the highest driving speed for the drum and in order to obtain a third speed, that is, the highest speed used, it has been necessary to drive the engine at an excessively high speed. The general object of this invention is to provide a simple construction applicable to the draw works mechanism as now used and without necessitating an increase in its length, but which will adapt the same for developing three driving speeds for the drum with one engine speed.

Further objects of the invention will appear hereinafter.

The invention consists in the novel parts and combination of parts to be described hereinafter, all of which contribute to produce an efficient three speed rotary draw works.

A preferred embodiment of the invention is described in the following specification while the broad scope of the invention is pointed out in the appended claims.

The drawing which consists of one figure is a side elevation and partial section showing the frame partially broken away with portions of the mechanism broken away and in section.

The rotary draw works mechanism comprises a drum shaft carrying a drum opposite to which there is mounted a driving shaft. In applying our invention, we provide a low speed driving connection between the shafts including a member rigid on one of the shafts and a loose member on

the other, with a clutch for driving through the low-speed connection at will; we also provide an intermediate-speed driving connection between the shafts including a member rigid on one of the shafts and a loose member on the other shaft, with its corresponding clutch for driving through the intermediate speed at will; we also provide a high speed driving connection between the shafts including a member rigid on one of the shafts and a loose member on the other shaft with its corresponding clutch for driving through the high speed connection, and we provide means corresponding to each clutch for operating the same independently.

We shall now describe this mechanism more in detail, and refer to the drawing in which 1 represents a drum shaft carrying a drum 2 rigidly keyed to it, said shaft being mounted on bearings supported on three posts, comprising two end posts 3 and 4 and an intermediate post 5. In the upper part of the frame a line shaft or driving shaft 6 is rotatably supported, and between these shafts 6 and 1 we provide three driving connections, any one of which may be employed at will to drive the drum shaft. On the driving shaft we provide a rigid low speed driving member which may be in the form of a driving sprocket wheel 7 which is connected by a sprocket chain 8 with an alining low speed sprocket wheel 9 which is loose on the shaft 1 and which is provided with its own clutch 10 adapted to be opened and closed at will by means of a lever 11. This low speed clutch 10 is similar in construction to an intermediate speed clutch 12 which is located at the other end of the shaft 1 between the posts 4 and 5 and which operates to connect a loose driven sprocket wheel 13 on the shaft 1, to the shaft when it is desired to drive the drum at an intermediate speed. This sprocket wheel 13 is in alinement with a driving sprocket wheel 14 on the shaft 6 and is driven from it by a sprocket chain 15. The movable member 16 of the clutch 12 may be shifted at will by means of a lever 17 fulcrumed at 18 and actuated by a foot lever 19 at the left of the frame. A spring 20 attached to the lever 17 normally holds this clutch open. The construction of this clutch 12 and the clutch 10 is substantially the same and these clutches are preferably one way drive clutches, that is to say, the

movable clutch member of each clutch is provided with a straight driving face, such as the face or shoulder 21 illustrated on the clutch 12, and an inclined or beveled face 22. The purpose of these beveled faces on these clutches will be described more fully hereinafter.

In order to enable the drum 2 to be driven at a high speed we provide a high speed driving member in the form of a sprocket wheel 23 which is loose on the driving shaft 6 and this sprocket wheel is connected by a chain 24 with an alining driven member in the form of a sprocket wheel 25. This sprocket wheel is keyed to the shaft 1 with the drum and if desired the longitudinal tie rods 26 of the drum may be extended through the sprocket wheel 25 and provided with nuts 27 which seat against the outer face of the sprocket wheel and secure the same to the drum. It should be understood, however, that these tie rods 26 do not necessarily do any driving because the sprocket wheel is keyed to the shaft, and through the shaft drives the drum.

The sprocket wheel 23 is driven through a suitable clutch 28 which is constructed with square jaws so that it will not release automatically once it has been closed.

The clutch member 29 may be closed at will by means of a foot lever 30 at the left of the platform or floor 31, which operates a link 32 connected with a bell crank lever 33, which in turn operates a horizontal link 34 connected with a clutch lever and fork 35, the fork of which connects with the movable clutch member. This lever 35 is fulcrumed at 36 and the spring 37 is attached to it and normally holds the clutch open.

The shaft 6 is driven continuously by means of a chain driven by an engine and running over the sprocket wheel 38 which is keyed to the shaft.

Means is provided on this shaft for driving the rotary table of the well and for this purpose the shaft 6 is provided with a sprocket wheel 39 controlled by a square jaw clutch 40 having a clutch lever 41 fulcrumed at 42 and operated by a lever 43 through a suitable link connection 44. The movable clutch member 45 of the clutch 40 is splined on the shaft like the other movable clutch members and when this clutch is closed the sprocket wheel 39 will be driven.

The ends of the shaft 6 project beyond the posts 3 and 4 and carry the usual continuously driven "nigger heads" 46.

With the organization of parts described above it will be evident that the chains 8 and 15 will be continuously driven but if the two clutches 10 and 12 are open the sprocket wheels 9 and 13 will rotate idly on the drum shaft. By closing either of these clutches the drum may be driven at low or intermediate speed.

When it is desired to drive the drum at high speed the two clutches 10 and 12 are left open but the clutch 28 is closed; closing this clutch 28 connects the sprocket wheel 23 to the shaft 6 and the chain 24 then drives the drum through the sprocket wheel 25.

It will be evident that if the high speed clutch 28 should be closed while the clutch 10 or the clutch 12 is in a closed condition, no harm will be done to the mechanism by reason of the beveled faces 22 of the clutches 10 and 12; the result would merely be that the shaft 1 would commence to rotate at a higher speed and this would throw open either the low speed clutch or the intermediate clutch.

As usually constructed two-speed draw works of this general type have a low speed drive at the left end of the drum as illustrated and the higher speed drive between the two posts 4 and 5. Our invention enables such a two-speed drive to be readily transformed into a three-speed drive simply by placing the sprocket wheel 25 between the post 5 and the adjacent end of the drum and at the same time placing a corresponding sprocket wheel and clutch on the driving shaft 6. However, it should be understood that with such a two-speed drive the clutch which is located between the posts 4 and 5 is a square jaw clutch, and for this reason it is necessary to move such square jaw clutch up onto the shaft 6 to drive the new sprocket wheel 23, and to substitute a bevelled jaw clutch 12 between the posts 4 and 5, as the driving connection at this point will now become an intermediate speed and must be constructed so as to throw out automatically in case the third or high speed is thrown in without throwing out the intermediate speed.

Where a two speed rotary draw works is transformed in this way the shaft 6 will have a key slot just to the left of the post 5 at which the loose sprocket wheel 23 must be placed. As the slot in the shaft at this point is a disadvantage, we provide bushings or sleeves 47 at this point which provide continuous cylindrical surfaces or bearing contacts for the hub of the sprocket wheel.

It is understood that the embodiment of the invention described herein is only one of the many embodiments this invention may take and we do not wish to be limited in the practice of our invention nor in our claims to the particular embodiment set forth.

What we claim is:

1. In a rotary drawworks mechanism, the combination of a frame having end posts and an intermediate post, a drum-shaft, a drum carried thereby with one end disposed adjacent to the intermediate post, a drive shaft mounted on the frame parallel with the drum-shaft, a driving connection and its

clutch located between one end of the drum and one of said end posts, another driving connection and its clutch for driving at another speed located between the intermediate post and the other end post and a third speed driving connection including a driven sprocket on the drum-shaft between the intermediate post and the adjacent end of the drum and a drive sprocket aligned relative thereto on the drive shaft, and a clutch on the drive shaft for said drive sprocket.

2. In a rotary drawworks mechanism, the combination of a frame having end posts and an intermediate post, a drum-shaft, a drum carried thereby with one end disposed adjacent to the intermediate post, a drive-

shaft mounted on the frame parallel with the drum-shaft, a low speed driving connection and its clutch located between one end of the drum and one of said end posts, an intermediate speed driving connection and its clutch located between the intermediate post and the other end post, and a high speed driving connection including a driven sprocket on the drum-shaft between the intermediate post and the adjacent end of the drum and a drive sprocket aligned relative thereto on the drive shaft, and a clutch on the drive shaft for said drive sprocket.

Signed at Torrance, Calif. this 14th day of June, 1923.

EDWIN W. GOESER.

WILLIAM D. DAVIDSON.
